UNITED STATES PATENT OFFICE

2,518,872

INDUCTION FURNACE

Ludwig A. Dreyfus, Västerås, Sweden, assignor to
 Allmanna Svenska Elektriska Aktiebolaget,
 Västerås, Sweden, a Swedish corporation

Application November 12, 1948, Serial No. 59,639
 In Sweden November 15, 1947

2 Claims. (Cl. 13—26)

1

In many electric eddy current furnaces a substantially uniform body, for instance a molten bath, is to be heated, and in such cases it is generally of minor importance if the electric induction in the furnace decreases towards its ends, as is usually the case. In certain cases, however, it may be of great importance that the induction be kept practically uniform for the whole length of the furnace, especially when a common inducing winding influences a plurality of electrically more or less independent bodies which, however, are to be heated uniformly, for instance for metallurgical reasons, or when there is only one body which for instance should be uniformly heat treated throughout its mass. When using a common cylindrical winding, it is known that the induction therein decreases towards the ends. If a uniform induction in the whole operative region of the furnace is desirable without any particular steps being taken as regards the winding, it will therefore be necessary to make the said operative region essentially shorter than the winding, so that the end portions having a reduced induction will be inactive. This implies, however, an imperfect utilization of the possibilities of the furnace.

According to the present invention, a more uniform distribution of the induction along the eddy current furnace is obtained by the provision of an inducing winding, which as a whole is connected in parallel with a condenser for compensating the main portion of its reactive power demand, while certain portions of the winding, especially the ends and the middle portion, are individually connected in parallel with separate positive or negative reactances by means of which the current density in the said winding portions can be adjusted to values other than the mean value of the winding. Thus for instance, negative reactances (capacities) may be connected in parallel to the end portions and a positive reactance (inductor) in parallel to the middle portion of the winding.

In the accompanying drawing, Fig. 1 shows diagrammatically in plan view an eddy current furnace having a plurality of bodies to be heated and Fig. 2 shows a vertical section thereof with the said bodies omitted but with lines of flux and level surfaces of the induction shown in the case of the invention not being applied. Fig. 3 shows a diagram of connections for one form of the invention and Fig. 4 shows a corresponding diagram of the current density in the winding.

In Figs. 1 and 2, the furnace winding is designated by 1 and a laminated iron shell surround-

2

ing the same by 2. Fig. 1 shows inserted into the furnace a number of bodies 3 to be heated, said bodies being only diagrammatically shown. The said bodies 3 may consist for instance of crucibles of conducting material or with a conducting content, of solid bodies for instance to be heat treated or of conducting carbon pieces for carburating a traversing gas current.

With a constant number of ampereturns per unit of length of the winding 1, the flux image shown in Fig. 2 is obtained, in which the full-drawn lines a designate magnetic lines of flux and the dotted lines b the level surfaces of the induction which are perpendicular to the flux lines. As shown, the distance between these level surfaces is essentially larger towards the ends of the furnace than in the middle height thereof, especially near the axis of the furnace, and as the induction is proportional to the inverse value of the said distance, it decreases essentially towards the ends of the furnace. In many cases it is, however, desirable that the induction is maintained at substantially the same value at the ends of the furnace as between the ends, and the present invention comprises means for increasing the number of ampereturns per unit of length of the furnace winding towards the ends for this purpose. In the form of the invention illustrated, condensers 4 are connected in parallel with the end portions of the furnace winding 1 and are preferably adjustable, while a middle portion is connected in parallel to an inductance 5, preferably also adjustable. The entire winding is as usual connected in parallel with a large condenser 6 which delivers the main portion of the necessary reactive power, while the active power is delivered by a generator 7. The result will be, that the number of ampereturns per unit of length of the winding, instead of being normally constant as in induction furnaces, will vary according to Fig. 4, in which the width of the hatched surface represents the said number, i. e., the number of ampereturns of the portions parallel with condensers will be somewhat increased and the said number of the portion parallel to an inductance will be somewhat reduced as compared with the portions without any parallel current path. By suitable adjustment of the members 4, 5, for instance under the influence of a pyrometer measuring the temperature in the different portions of the furnace, the specific number of ampereturns along the furnace winding can be varied so that the reduction of the magnetic induction towards

the ends of the furnace illustrated in Fig. 2 is essentially compensated.

The invention may of course be combined with other means for equalizing the induction in the furnace body, for instance with the internal inductor winding surrounded by the bodies heated by the induction described in my patent application Serial No. 59,705 of even date. In such case also certain portions of the internal winding, for instance in the middle and at the ends, may be 10 provided with parallel reactances in the same way as the portions of the winding 1.

I claim as my invention:

1. An eddy current furnace comprising a coil-shaped inductor winding, a source of high frequency current, means connecting the ends of the coil to said source, conducting means inside said winding adapted to be uniformly heated by eddy currents induced therein by said winding, a variable inductance connected in parallel with the middle portion of said winding and variable capacitors connected in parallel respectively with each end portion of said winding beyond the points of connection of the inductance. 15

2. In a furnace as claimed in claim 1, a laminated iron shell surrounding said winding. 25
